UNITED STATES PATENT OFFICE.

OTIS A. MYGATT, OF NEW YORK, N. Y.

DESIGN FOR A REFLECTOR FOR INCANDESCENT ELECTRIC LAMPS.

No. 37,833.

Specification for Design.

Patented Feb. 20, 1906.

Application filed July 17, 1905. Serial No. 270,142. Term of patent 14 years.

To all whom it may concern:

Be it known that I, OTIS A. MYGATT, a citizen of the United States, residing at New York, in the county of New York and State of New York, have invented a certain new, original, and ornamental Design for a Reflector for Incandescent Electric Lamps, of which the following is a specification, reference being had therein to the accompanying drawings, forming part thereof.

Figure 1 is a side elevation of the reflector

according to my design. Fig. 2 is a perspective view as seen partly from above. Fig. 3 is a perspective view as seen partly from below.

I claim—

The ornamental design for a reflector for incandescent lamps, as shown.

OTIS A. MYGATT.
